Garretson Smith & Henry Brown, of Philadelphia, Pa.
Assignors to Cos. Whitman & Cox, of same place.
Letters Patent No. 1167. Dated Nov. 1. 1859.

The schedule referred to in these Letters Patent and making part of the same.

To all whom it may concern:

Be it known, that W's G. Smith and H. ... Brown of Philadelphia in the County of Philadelphia and State of Pennsylvania, have invented or produced a new and original Stove Design called The Brilliant Gas Burner, and we do hereby declare that the following is a full, clear and exact description of the same, reference being had to the annexed drawing forming part of this specification,

Which represents a perspective view of the Base, Top, and Door Frame.

This design is for a Gas Burning Stove, the ornamental castings consisting of the Base, Top, and Door Frame,

The base of the form shown in the drawing, the edge of the lower plate being surrounded with a border of figures represented in the drawing by letter a, with the flower and foliage b, at the corners.

The ash pit plate is ornamented with two rows of figures c, and d, on each side of the draft opening o, and the rising part of the base is ornamented with flowers e. The whole design being in Bass. Relief and as represented by the annexed drawing.

The top is of the form shown in the drawing and rises dome-like, the outer edge having the figures g, around the edge with the foliage F, at the corners, as shown by the drawing.

The rising part of the top is ornamented with figures h, and i, they being placed alternately around it.

The top has the scroll and foliage j, on each side of the form, and the rear part of the top is decorated with the configuration K, composed of scrolls and foliage. These ornaments being all in Bass. Relief and of the form shown in the accompanying drawing.

The door frame has the bordering of ornaments l, around the edge and the scroll s, around the openings immediately under the door, which is of the shape shown in the drawing, and has the scrolls and foliage m, and n in Bass. Relief in the corners, as represented by the drawings.

We claim the design and configuration in Bass. relief, on the ornamental castings, for a Stove design, as above set forth, and represented by the annexed drawing.

For testimony whereof we have hereunto signed our names before two Subscribing Witnesses.
